APPARATUS FOR ATTACHMENT TO FURNITURE
John B. Daniell, 911 14th St., Santa Monica, Calif.
Filed Oct. 19, 1959, Ser. No. 847,430
4 Claims. (Cl. 248—230)

This invention generally relates to an apparatus for attachment to furniture, and more particularly concerns an apparatus which may be attached to a furniture frame member (for example, an arm, leg, or frame structural member) which may be employed for the purpose of supporting a tray, glass receptacle, ash tray, or the like. The invention has been primarily designed for its application in conjunction with the retention of a tray in a convenient supported position from a furniture piece for the purpose of holding glasses, plates, and other containers and receptacles for beverage and food. Even more specifically, the invention is believed to have its greatest utility in respect to its use on various different types of patio furniture including lawn swings, chairs, and chaise lounges.

It will be appreciated, however, that the present invention for an apparatus for attachment to furniture may be employed in a variety of applications for different purposes of an analogous nature.

It will be evident to those skilled in the art that many different types of attachments have been developed for coupling to particular furniture frame members. Certain of these devices have been marketed with limited success. However, the prior art constructions have for the most part been limited to specific uses in conjunction with particular furniture frame members. In other words, furniture frames are constructed in many different ways as concerns the shape of the frame member, its structural position with respect to the overall piece of furniture, and its relationship to other frame elements. As a consequence, it has been extremely difficult to provide an attachment for furniture which is versatile enough to be applied to several different types of furniture frames and yet which is simple to construct and may be conveniently manipulated.

It is therefore an object of the present invention to provide an attachment for furniture, particularly adaptable as a means of supporting a tray or the like, which may be simply constructed of a minimum number of parts, and yet which may be conveniently manipulated and adjusted to meet the individual user's requirements.

Another object of the present invention is to provide an attachment for furniture primarily adapted for use in supporting a tray or equivalent structure which is so designed that it may be respectively applied to various different types of frame members with a minimum number of adjustments.

Another object of the present invention is to provide an attachment for furniture primarily adapted for use in conjunction with a tray or the like, which may be readily positioned relative to the furniture frame such that the tray attaching portion thereof may be located in almost any given plane.

Still another object of the present invention is to provide an attachment for furniture particularly adaptable for use with a tray structure, which is ruggedly constructed and which may be produced on an economical basis.

These and other objects of the present invention are generally achieved by providing in accordance with the present invention an apparatus for clamping to a furniture frame member which comprises a supporting member designed to extend across and into engagement with one side portion of the frame member. Clamping means are designed to engage an opposite side portion of the frame member, and coupling means are provided to connect the

2

clamping means to the supporting member. The coupling means enables pivotal movement of the supporting member with respect to the clamping means.

The supporting member necessarily has a portion, preferably angled, which is spaced from the frame member for retaining a tray or equivalent receptacle by means of an adapter.

A better understanding of the present invention will be had by reference to the drawings, showing merely illustrative embodiments, and in which:

FIGURE 1 is a perspective view of the furniture attachment apparatus of the present invention illustrating its connection or coupling to a tubular furniture frame member;

15 FIGURE 2 is a modified embodiment of the furniture frame attachment apparatus of FIGURE 1, illustrating its attachment to an angular frame member;

FIGURE 3 is a top elevational view of a portion of the apparatus shown in FIGURE 2;

20 FIGURE 4 is a view of a part of the furniture frame attachment apparatus of FIGURE 1 shown in a different mounting position; and,

FIGURE 5 is an isometric view of two fittings adaptable for use with the furniture attachment apparatus of FIGURE 1.

Referring now to the drawings, there is shown in FIGURE 1 a tubular member 10, which may comprise any frame member of a piece of furniture. In the usual application, the frame member 10 will consist of a portion of 30 a leg of a patio chair or the like. Coupled to the tubular member 10 is a supporting arm generally designated by the numeral 11. The supporting arm 11 co-operates with a clamping member 12, the latter being coupled to the supporting arm and to the other side of the tubular member 10. The supporting arm 11, in turn, has coupled at its outer end an adapter in the form of a tray holder 13.

The individual components of the furniture attachment apparatus may now be described in greater detail. The supporting arm 11 includes a main elongated body portion 14 of rectilinear construction which terminates at one end in an overlapping portion 15 turned back at 16. At its other end, the supporting arm 11 merges into an angled portion 17, which in turn terminates in the supporting portion 18. The plane of the supporting portion 18 is preferably at right angles to the plane of the rectilinear body portion 14 of the supporting arm 11.

The supporting arm 11 defines therein in its overlapping portion 15 and opening 19. In its supporting portion 18, the arm 11 further defines a plurality of openings 20a, 20b, and 20c. The functions of these different openings will become clearer as the specification proceeds. The openings 20a, 20b, and 20c may be more clearly seen in the view of FIGURE 4. The supporting arm 11 further defines in its body portion 14 an elongated slot 21, more clearly seen in the view of FIGURE 2.

60 The clamping means 12 generally comprises a U-shaped portion 22 integrally connecting with a first lateral portion 23 adapted to co-operate with the overlapping portion 15 of the supporting arm 11. Towards this end a nut and bolt assembly 24 may be adapted to be received through the opening 19 in the overlapping portion 15 to extend through one of a plurality of openings 25 provided in the lateral portion 23 of the clamping means 12. As shown in FIGURE 1, the nut assembly 24 is coupled through the opening 19 of the overlapping portion 15 and the center one of the openings 25 defined in the lateral portion 23 of the clamping means 12.

65 The clamping member 12 further includes a second lateral portion 26 which defines therein an elongated arcuate slot 27. A nut and bolt assembly 28 is adapted to be received through the slot 26 and coupled to the supporting arm 11 through the slot 21 previously identi-

fied. Additionally, a threaded opening 29 may be provided in the base of the U-shaped portion 22 of the clamping means 12 for the purpose of retaining a fitting as will be hereafter described.

The tray holder 13 preferably comprises an angle member consisting of, as viewed in FIGURE 1, a horizontal portion 30 and a vertical portion 31. The horizontal portion 30 is provided with a nut and bolt structure 32 designed for attachment to and the holding of a tray, glass receptacle, ash tray, or the like. The vertical portion 31 of the tray holder 13 defines therein an opening for receiving a nut and bolt structure 33, which in the view of FIGURE 1 co-operates with an opening 20b (seen in the view of FIGURE 4) for firmly securing the tray holder to the supporting portion 18 of the arm 11. Another nut and bolt structure 33 extends through an arcuate slot 35 in the vertical portion 31 for coupling to the supporting portion 18, as through an opening 20c (not seen in the view of FIGURE 1) as more clearly shown in the view of FIGURE 4.

The operation of the improved furniture attachment apparatus of the present invention may now be described. In order to couple the attachment to the tubular frame member or leg 10, the clamping means 12 would normally be separated from or at least loosened with respect to the supporting arm 11 such that these two components may be passed over or around the tubular member 10. Supporting arm 11 would be positioned against one side portion of the frame member 10 and the clamping means positioned over the other side portion of the tubular frame member 10. The nut and bolt means 28 would then be coupled through the slot 27 of the clamping member 12 and through the slot 21 of the arm 11. Similarly, the nut and bolt means 24 would be coupled through the opening 19 of the overlapping portion 15 of the supporting arm 11 and through one of the openings 25 of the lateral portion 23 of the clamping means 12. Of course, in this respect, another opening (not shown) must be provided in the rectilinear portion 14 of the supporting arm 11 aligned with the opening 19 in the overlapping portion 15 thereof.

In coupling the clamping means 12 to the supporting arm 11, certain adjustments may be made with respect to the spatial position of the supporting arm 11. Thus, assuming that the nut assembly 24 is coupled through the center one of the openings 25 in the lateral portion 23, the supporting arm 11 may be pivoted with respect to the axis of the nut and bolt assembly 24 throughout the arc of the slot 27 and the nut 28 thereafter secured in the particular position desired. For even more acute angular adjustment, the nut and bolt assembly 24 may be moved so as to extend through one of the outer openings 25, whereby a greater relative pivoting of the arm 11 may be accomplished in either, respective, direction.

It should be noted at this time that the nut and bolt means 24 and 28 preferably embodies wing nuts which may be conveniently manually loosened or tightened according to the requirements of the individual user. Similarly, the nut and bolt means 34 preferably embodies a wing nut for convenient adjustment. The other nut and bolt assemblies 32 and 33, as indicated, may include conventional nuts since these assemblies are relatively fixed for most requirements.

After the clamping means 12 has been secured about the tubular member 10 to the supporting arm 11, a further adjustment may be made as between the tray holding support or adapter 13 and the supporting portion 18 of the supporting arm 11. Thus, the tray holding structure 13 may be pivoted about the nut and bolt assembly 33 enabling the nut and bolt assembly 34 to be positioned in any given portion of the slot 35. Furthermore if it is desired to have the tray holding adapter 13 positioned in line with the supporting portion 18, the nut and bolt assemblies 33 and 34 may be loosened and removed. Thereafter, the tray holding adapter 13 may be rotated

90 degrees to a position such as shown in FIGURE 4. Thereafter, the nut and bolt assembly 34 may be positioned through either the opening 20b or 20c to be in line with the slot 35. Correspondingly, the nut and bolt assembly 33 may be positioned through the opening 20a of the supporting portion 18 of the arm 11.

It will be appreciated as a consequence of the various adjustments described, that the furniture attachment apparatus may be spacially positioned to a horizontal plane regardless of the particular angle or location of the tubular frame member 10 with respect to the normal sitting position of the user.

In the modification of FIGURE 2, the furniture attachment apparatus of FIGURE 1 has been shown in another form for attachment to an angular frame member 36. The angular frame member 36 comprises one portion 37 at right angles to another portion 38.

With such a frame member, the clamping means 12 is replaced by the clamping means 39 as shown in FIGURE 2. The clamping means 39, as perhaps more clearly seen in the view of FIGURE 3, comprises a first generally U-shaped portion 40 integrally formed with and at right angles to a second U-shaped portion 41. In using the clamping means of FIGURES 2 and 3, the U-shaped portion 40 of the clamping member 39 is positioned against the portion 37 of the angle member 36 with the U-shaped portion 41 being connected over one edge thereof. Thereafter, the supporting arm 11 is positioned such that the overlapping portion 15 extends in turned back relation over an edge of the portion 38 of the angled frame member 36. With the supporting arm 11 and clamping member 39 so positioned, a bolt and nut assembly 42 may be passed through appropriate openings provided in the U-shaped member 40 to couple the clamping means 39 to the arm 11 through the slot 21 provided therein.

In the event that the tubular member 10, again referring to FIGURE 1, is of a lesser diameter or cross section than properly will fit the co-operating clamping means 12 and supporting arm 11, various type fillers may be employed. In this regard, there is shown in FIGURE 5 an arcuately shaped segment 43 adapted to be received on the underside of the U-shaped portion 22 of the clamping means 12 of FIGURE 1 and attached thereto through an opening 44 provided therein to co-operate and be aligned with the opening 29 provided in the U-shaped portion 22. A suitable screw would be threaded into the openings 29 and 44 to couple the two units together. Similarly, if necessary, another filler 45 could be applied to the rectilinear body portion 14 of the arm 11 between the body portion 14 and the frame member 10 by the use of an appropriate screw hole 46 provided in the filler 45 and adapted to be aligned with a similar screw hole (not shown) provided in the rectilinear body portion 14.

From the foregoing description, it will be appreciated that the furniture attachment apparatus of the present invention may be applied to relatively diverse furniture frame shapes and structure, regardless of size or particular orientation with respect to the overall furniture piece and position of the individual user thereof. In addition, it will be appreciated that the furniture attachment apparatus of the present invention enables a simple yet rugged construction which may be manufactured economically on a production line basis.

Although certain preferred embodiments have been shown and described, it will be appreciated that many modifications and changes may be made within the scope and spirit of the present invention.

What is claimed is:

1. An apparatus for clamping to a furniture frame member, said apparatus comprising: a supporting member designed to extend across and into engagement with one side portion of said frame member, said supporting member having an angled end portion spaced from said

frame member; clamping means designed to engage an opposite side portion of said frame member; pivotable coupling means connecting said clamping means to said supporting member, said coupling means enabling pivotal movement of said supporting member with respect to said clamping means, adapter means designed for attachment to said angled end portion of coupling to a receptacle structure; and, adjustable coupling means co-operatively provided on said angled end portion and said adapter means for canting said adapter means at various angles with respect to said end portion.

2. The combination, according to claim 1, in which said adapter means comprises an angled member having one portion thereof secured to said end portion through said adjustable coupling means.

3. An apparatus for clamping to a furniture frame member said apparatus comprising: a supporting member designed to extend across and into engagement with one side portion of said frame member, said supporting member having an angled end portion spaced from said frame member for retaining a tray holding structure; clamping means including a generally U-shaped portion designed to engage an opposite side portion of said frame member, said clamping means including a first lateral portion designed for fixed engagement with said supporting member 25 and a second lateral portion designed for movable en-

gagement with said supporting member so as to enable pivotal movement of said supporting member with respect to said first lateral portion.

4. An apparatus for clamping to a furniture frame angle member, said apparatus comprising: a supporting member designed to extend across and into engagement with one angular portion of said frame member, said supporting member including a turned back portion designed to be received over an edge of said one angular portion; 10 clamping means designed to engage the other angular portion of said frame member, said clamping means comprising a first U-shaped member designed to be received over the edge of said other angular portion and a second U-shaped member integrally formed with said first U-shaped member, said second U-shaped member, being designed to have its open end portion engage a side of said other angular portion; and, coupling means connecting said clamping means to said supporting member.
